UNITED STATES PATENT OFFICE.

PETER E. GELDHOF, OF SYRACUSE, NEW YORK, ASSIGNOR TO SYRACUSE WASHING MACHINE CORPORATION, OF SYRACUSE, NEW YORK, A CORPORATION OF NEW YORK.

LUBRICATING SYSTEM FOR POWER-DRIVEN WASHING MECHANISM.

Application filed May 7, 1925. Serial No. 28,604.

This invention relates to a clothes washing machine in which a plunger is reciprocally movable thru a guide tube in the bottom of the vat or tub by means of a power-driven rock arm which is fulcrumed at one end to a swinging link on the frame of the machine and has its other end operatively connected to the plunger while its intermediate portion is connected by a pitman to a suitable power driven crank shaft for imparting rocking movement thereto and thereby transmitting reciprocal motion to the plunger and to the washing mechanism carried thereby.

15 The main object of the invention is to provide a more efficient means for lubricating the various bearings on the moving parts from a single reservoir and to arrange the reservoir in such manner that the oil may be conveniently refilled by the operator without laborious exertion or danger from the operation of the moving parts.

20 Other objects and uses relating to specific parts of the oiling system will be brought out in the following description.

In the drawings:

Figure 1 is a vertical sectional view of a portion of a washing machine showing the parts to be lubricated from the same source of supply.

Figure 2 is an enlarged vertical sectional view taken on line 2-2, Figure 1.

Figure 3 is a top plane of the detached oil reservoir and adjacent portions of the distributing pipes leading therefrom.

Figure 4 is an enlarged transverse sectional view taken in the plane of line 4-4, Figure 1.

In order that the invention may be clearly understood I have shown a platform -1- of the main supporting frame upon which the bottom of the tub or vat as -2- is adapted to rest.

A tubular post -3- extends thru a central opening in the bottom of the vat and is provided with opposed flanges -4- and -5- adapted to engage the upper and lower faces of said bottom, the lower end of the tubular post -3- being threaded and engaged by a nut -6- which also engages the lower flanged member -5- for clamping the post and member -5- in operative position on the bottom of the vat.

A plunger -7- is reciprocally movable in

the tubular post -3- and is adapted to carry at its upper end a suitable washing mechanism, not necessary to herein illustrate or describe, the lower end of the plunger being reduced and threaded for receiving a suitable nut -8.

A collar -9- is secured to the plunger -7- between the nuts -6- and -8- a sufficient distance from the nut -6- to allow the desired vertical movement of the plunger and washing mechanism carried thereby within the vat -2-.

An additional collar -12- is loosely mounted upon the upright shaft -7- directly below the collar -9- and disk -11- for frictional engagement with said disk and is adapted to cooperate with the collar -9- and interposed disk -11- to form a frictional drive clutch for transmitting rotary motion to the plunger in a manner and for a purpose hereinafter described.

A yoke -13- is loosely mounted upon the shaft or plunger -7- between the lower face of the collar -12- and nut -8- and is provided with opposite radially projecting studs -14- for receiving the adjacent bifurcated end of a vertically movable operating lever -15- which extends radially from the collar -13- and shaft -7- toward one side of the tub and has its other end pivotally connected at -16- to the lower end of a swinging link -17- said link having its upper end pivotally connected at -18- to a suitable bracket -19- on the underside of the platform -1- thus permitting the link to swing inwardly and outwardly as the lever -15- assumes different angular positions about the axis of the pivot -16- for producing a rectilinear motion of the plunger -7-.

A driving shaft -20- is journaled in one side of a gear case -21- on the underside of the platform -1- and is adapted to be driven by any suitable source of power, not necessary to herein illustrate or describe.

The crank arm -22- is pivotally connected at -23- to one end of a pitman -24-, the latter having its other end pivotally connected at -25- to the intermediate portion of the lever -15-, said pitman serving to transmit reciprocal rocking motion to the lever as the crank shaft -20- is rotated.

An additional rock arm -26- is pivoted

at one end at —27—to the gear case —21—and has its other end pivoted at 28 to the lever —15—between the pivots —16— and —25—for causing the inner end of the lever 5 —15—to travel as nearly as possible parallel with the axis of the shaft —7—.

A coiled spring —29—is connected at one end to the underside of the platform —1—and has its other end connected to the lever 10 —15—to assist in raising the inner end of the lever and plunger —7—together with the parts carried by said plunger and thereby to reduce the load upon the motor power transmitted to the shaft —20—.

15 *Lubricating system.*

An oil reservoir —30—is secured by bolts —31—to the underside of the platform —1—near the periphery thereof so that one 20 end of the reservoir may protrude slightly beyond said periphery to permit the convenient refilling of the reservoir with oil when desired.

As illustrated this reservoir is provided 25 with a plurality of, in this instance, three oil receiving pockets —32,—32'— and —32''— which extend slightly beyond the periphery of the platform —1— where the projecting ends are normally covered by a 30 movable closure —33— which is hinged at one end at —34—to the adjacent edge of the reservoir and has its other end provided with a finger piece —35— by which it may be rocked to and from its closed position as 35 may be necessary for refilling and protecting the oil containing pockets against accumulations of dust and other foreign matter.

The upper edge of the lever —15—is provided with a lengthwise oil containing channel or pocket —36— having branch passages —37,—38—and —39— leading respectively to the pivotal bearings —25,—28—and —16—, said channel also containing a 45 lengthwise strip —40— of felt or equivalent absorptive material capable of retaining a considerable quantity of oil absorbed thereby for continuous distribution thru the branch passages —37,—38,— and —39—to their respective bearings.

The upper end of the pitman —24—is provided with an oil pocket —41—in which is placed a felt or other absorbent wick —42— having a portion thereof projected upwardly to form a wiper —43—for a purpose presently described, the pocket —41— being provided with branch passage —44— leading to the pivotal bearing —23—for lubricating the same.

The upper end of the link —17—is also 60 provided with an oil pocket —45— having a discharge passage —45'— thru the bottom thereof and directly over the corresponding end of the channel —36—in the lever —15—to allow the oil from the pocket —45—to 65 gradually drop into the underlying portion

of the channel —36—and on to the adjacent end of the felt strips —40—which when saturated serves to distribute the oil to the several branch passages —39,—38—and —37—and thence to the corresponding pivotal 70 bearings previously mentioned.

The friction collar —12—is provided with a radial extension —12'— having an oil receiving pocket —46— which communicates thru a branch passage —47— with a radial 75 channel —48— in the adjacent side of the opening for the shaft —7—for lubricating the bearing of said collar upon the shaft and also lubricating the contiguous end-thrust bearing faces of the collar —12—and 80 yoke —13—.

The upper end of the yoke —13—is also provided with oil passages —49—and branch 85 passages —50— leading therefrom to the ends of the yoke for lubricating the pivotal connections between the yoke and adjacent ends of the lever —15—as shown more clearly in Figure 2.

The reservoir —30—is preferably arranged directly over the upper end of the link 90 —17—and has one of its pockets as —32'— provided with a downwardly extending discharge tube —51— leading from the bottom thereof directly into the oil well —45—in the upper end of the link —17—.

The pocket —32—is provided with an inwardly and downwardly extending pipe —52— having its discharge end —52'— directly over the oil pocket —46—in the collar —12—for supplying oil thereto. The pocket —32'— is also provided with an inwardly and downwardly projecting pipe —53— having its inner end disposed directly over and in close proximity to the wiper —43—in the upper end of the pitman —24— so that 105 as the pitman is moved lengthwise of the pipe —53— by the rotation of the crank arm —22—the wiper —43— will intermittently brush across the open inner end of the pipe —53—to transfer oil therefrom into the 110 pocket —41—and thence to the passage —44—to the adjacent bearing —23—.

The various oil passages leading from the reservoir —30—and from the pockets —41,—45—and —46—and also from the channel —36—are relatively small or restricted to conserve the flow of oil therethru while the absorbent members —42—and —40—serve to retain and to distribute the oil deposited in their respective chambers to 120 the passages leading therefrom.

The inner end of the lever —15—is provided with opposed shoulders —54—and —54'—in longitudinally spaced relation for engaging a lug —55— on the collar —12— as the lever —15—is rocked vertically from one extreme position to the other for imparting an intermittent rotary motion to the plunger shaft —7—and washing mechanism carried thereby and causing said washing 125 130

mechanism to gradually change position for contact with different portions of the clothes.

For example, as the shaft 20 is rotated, vertical rocking movement will be transmitted to the lever 15 thru the medium of the pitman 24 for reciprocating the yoke 13 rectilinearly or vertically a distance equal to the throw of the adjacent end of the lever.

Now, as the yoke 13 is moved upwardly it will force the collar 12, disk 11, and collar 9 together with the shaft 7 in the same direction and as these parts approach the limit of their upward movement the shoulder 54 will engage the adjacent side of the lug 55 and thereby effect a slightly angular movement of the collar 12 and thru the medium of the friction disk 11 will also produce a corresponding angular movement of the collar 9, shaft 7 and parts carried by said shaft.

Under these conditions the weight of the shaft 7 and parts carried thereby will be borne by the disk 11 and collar 12 to produce sufficient friction for effecting the angular movement of the shaft.

Now, as the lever 15 is moved downwardly, the resistance of the washing mechanism against the clothes and washing fluid in the vat 2 will tend to oppose the downward movement thereby effecting a release of the friction grip between the collars 9 and 12 for retaining the shaft 7 and parts carried thereby in the angularly adjusted position so that when the lever approaches the limit of its downward movement the shoulder 54 will engage the adjacent side of the lug 55 and restore the collar 12 to its starting position, the oil pocket 46, the extension 12 being of sufficient circumferential length to maintain registration with the adjacent end 52 of the pipe 52 in all positions of angular adjustment of the collar 12.

During these operations of the various moving parts the oil from the reservoir 30 will be slowly fed, preferably drop by drop to the pockets 45, 41 and 46, the oil from the pocket 45 being allowed to pass drop by drop thru the restricted passage 26 on to the underlying end of the channel 36 and thence thru the restricted passage 39 to the bearing 16.

The oil deposited in the pocket 41 will flow drop by drop thru the passage 44 to the bearing 23 while the oil deposited in the pocket 46 will flow thru the restricted passages 47, 48, 49 and 50 to the adjacent portions of the shaft 7 and to the trunnions 14.

The oil which is deposited in the channel

36 will be partially taken up by the wick 40 and distributed thru the restricted passages 37 and 38 to the bearing 28 and 25, it being understood that the oil in the pocket 45 will also lubricate the bearing 18 thus completing the automatic lubrication of the various bearings from a single source of supply such as the reservoir 30. In this connection reference is made to the pending application of G. C. Wilkinson, Hedglon and Geldhof, Serial No. 707,141, filed May 17, 1924, in which applicant is one of the joint inventors.

What I claim is:

1. The combination with a lever supporting link, a lever actuating pitman, a lever actuated yoke, a lever having separate pivotal connections with the length, the piston and the yoke, an oil reservoir, and means for conducting oil from said reservoir to the several pivotal connections.

2. The combination with a wash tub, a supporting frame therefor, a shaft reciprocally movable vertically thru an opening in the bottom of the tub, a bearing for the lower end of the shaft provided with radially projecting trunnion bearings, a lever pivotally connected to said trunnion bearings, means for rocking the lever in reverse directions for reciprocating the shaft bearing vertically, means for transmitting motion from the shaft bearing to the shaft including an angularly adjustable collar having an oil pocket communicating with the shaft bearing and with the trunnion bearings, of an oil reservoir, and means for conducting oil from said reservoir to the oil pocket.

3. In a power driven washing mechanism, a vertically movable plunger, a lever pivoted to swing about a horizontal axis and operatively connected to the plunger for reciprocating the same, a power driven crank shaft, a pitman actuated by the crank shaft and pivotally connected to the lever for rocking said lever about its pivotal axis, said lever having a lengthwise oil channel in its upper side provided with branch oil passages leading to both of said pivots, and automatic means for depositing oil into said channel to flow along said channel from one pivot to the other as the lever is rocked vertically by the pitman.

4. A power driven washing mechanism as in claim 3 in which an oil absorbent strip is seated in said channel and extends from one pivot to the other pivot for controlling the distribution of oil in the channel to both of said pivots.

5. In a power driven washing machine having a wash tub and a plunger movable vertically through an opening in the bottom of the tub, means for operating said plunger including a lever support, a pitman and a

lever having a journal bearing on the support and a pivotal bearing for the link, said lever having a lengthwise oil channel in its upper side communicating with both of said 5 pivotal bearings and connections between the lever and plunger for reciprocating said plunger.

6. In a power driven washing mechanism having a wash tub and a plunger movable 10 vertically through an opening in the bottom of the tub, means including a friction clutch for reciprocating said plunger and for imparting thereto an intermittent angular motion as the plunger is reciprocated in reverse 15 directions, one of the clutch members being loosely mounted on the plunger below its companion clutch member for angular movement relatively to the plunger and provided with an oil pocket communicating with its 20 bearing on the plunger for lubricating the same, and means for automatically feeding oil into said pocket.

7. In a power driven washing mechanism having a wash tub, a plunger movable vertically 25 through an opening in the bottom of the tub, and a supporting frame for the tub in combination with a link having its upper end pivoted to the frame and provided with an oil pocket, a lever having one end pivoted 30 to the lower end of the link and its other end operatively connected to the plunger for reciprocating the same, means including a crank and pitman for operating said lever to reciprocate the plunger, said pitman having 35 pivotal connection with the intermediate portion of the lever, the lever being provided with an oil channel in its upper side communicating with the pivotal connections of the lever with the link and pitman for supplying 40 oil to both of said pivots an oil reservoir in a plane above the pocket in the upper end of the link, means for feeding oil from the reservoir into the pocket, and means for feeding oil from the pocket into the channel 45 in the upper side of the lever.

8. In a power driven washing mechanism having a wash tub and a plunger movable vertically through an opening in the bottom of the tub in combination with means for reciprocating said plunger including a rotary 50 crank arm and a pitman pivotally connected to said crank arm and provided with an oil pocket in its upper end communicating with the pivotal connection between the crank 55 arm and pitman, an oil reservoir, and means for feeding oil from the reservoir to the oil pocket in the upper end of the pitman.

9. In a power driven washing mechanism, a lever pivoted to swing vertically about a 60 horizontal axis, power driven means for operating said lever, a yoke pivoted to said lever to be reciprocated vertically thereby, an upright plunger journaled in said yoke 65 for relative angular movement therein, said

yoke having oil passages therein leading to 65 its pivotal connection with the lever and to its bearing for the plunger, a collar loosely mounted on the plunger above the yoke and provided with an oil pocket communicating with the oil passages in the yoke and with its 70 journal bearing for the plunger, connections between the lever and collar for effecting the angular movement of the collar as the lever is rocked in reverse directions, means for transmitting said angular movement from 75 the collar to the plunger, and automatic means for depositing oil in said pocket during said angular and reciprocatory movements.

10. In a power driven washing mechanism, 80 a wash tub, a supporting frame for the wash tub, an upright link having its upper end pivoted to the frame and provided with an oil pocket communicating with the pivotal bearing for the link, an oil reservoir 85 supported on the frame above said pocket, means for conducting oil from the reservoir to the pocket, a lever having one end pivoted to the lower end of the link to swing vertically and provided with a lengthwise oil 90 channel in its upper side communicating with its pivotal connection with the link, means for discharging oil by gravity from said pocket into the channel, a yoke pivotally mounted upon the other end of the lever 95 to be reciprocated vertically thereby, a plunger carried by said yoke, and movable vertically therewith through an opening in the bottom of the wash tub, a crank shaft 100 between the yoke and link, and a pitman 10 actuated by the crank shaft and pivotally connected to the intermediate portion of the lever for rocking the same about its pivotal 105 connection with the link and thereby reciprocating the yoke and plunger, said lever having an oil passage leading from its pivotal connection with the pitman to the oil 110 channel in the upper side of the lever for receiving oil therefrom.

11. In a power driven washing mechanism, 115 a wash tub, a supporting frame for the tub, an upright link having its upper end pivoted to the frame and provided with an oil pocket communicating with its pivotal connection with the frame, an oil reservoir 120 supported on the frame above the link and discharging by gravity into said pocket, a plunger reciprocally movable vertically through an opening in the bottom of the tub, and means including a lever pivoted to the 125 lower end of the link for reciprocating said plunger, said lever having a lengthwise channel in its upper side communicating with its pivotal connection with the link, said oil pocket in the upper end of the link 130 being provided with means for discharging oil therefrom into said channel.

12. In a power driven washing mecha-

nism, a lever pivotally supported at one end to rock vertically, a yoke pivotally mounted upon the other end of the lever to be reciprocated thereby, a vertically movable plunger actuated by the yoke, a crank shaft having a pitman pivotally connected to the intermediate portion of the lever for operating the same, said yoke and lever having oil passages leading to the several pivots, an oil reservoir in a plane above said pivots and provided with means for feeding oil by gravity therefrom to the several pivots.

13. In a power driven washing mechanism, a lever pivotally supported at one end to rock vertically, a yoke pivotally mounted upon the other end of the lever to move therewith, a plunger actuated by the yoke, a crank shaft, and a pitman having its upper end pivoted to the crank shaft and provided with an oil pocket communicating with the adjacent pivot to supply oil thereto, the lower end of said pitman being pivotally connected to the intermediate portion of the lever, an oil reservoir in a plane above the pivoted end of the lever and provided

with means for discharging oil therefrom into the pocket in the upper end of the pitman.

14. In a power driven washing mechanism, a lever pivotally supported at one end to rock vertically, a yoke pivotally mounted upon the other end of the lever to move therewith, a plunger journaled in the yoke to move vertically therewith and having an independent angular movement, means actuated by the vertical rocking movement of the lever for effecting an angular movement of the plunger in one direction relatively to the yoke, said means including a friction collar tight on the shaft and a companion friction collar loose on the shaft between the tight collar and yoke, said loose collar and yoke being provided with oil passages leading to the plunger and to the pivotal connection of the yoke with the lever, and means for automatically feeding oil by gravity to the passage in the collar.

In witness whereof I have hereunto set my hand this 29th day of April, 1925.

PETER E. GELDHOF.
